UNITED STATES PATENT OFFICE

CHARLES E. PHARO, OF CORTEZ, COLORADO

AUTOMATIC TRAIN-PIPE COUPLING

Application filed June 22, 1926. Serial No. 117,783.

This invention relates to a coupling for automatically connecting and establishing communication between the air and steam pipes of railway cars during the coupling of the cars, and includes among its objects the provision of improved means for coupling steam and other pipes of railway cars; the provision of means such that the coupling of train pipes may be accomplished automatically and without intervention of a brakeman or other train man; and such other objects, advantages and capabilities as will hereafter appear and as are inherent in the construction disclosed herein. My invention further resides in the construction, combination and arrangement of parts illustrated in the accompanying drawings and, while I have shown therein what is now believed to be the preferred embodiment of my invention, I desire this disclosure to be construed as illustrative only and not in a limiting sense.

In the accompanying drawings, in which is illustrated what is now considered the preferred embodiment of my invention,

Figure 1 is a top plan view of an air and steam pipe coupling constructed in accordance with my invention,

Figure 2 is a view partly in elevation and partly in vertical section, illustrating the coupling applied to two railway cars,

Figure 3 is a view in front elevation of one section of the coupling,

Figure 4 is a bottom plan view of the coupling,

Figure 5 is a sectional view taken on the vertical plane indicated by the line 5—5 of Figure 1,

Figure 6 is a sectional view taken on the vertical plane indicated by the line 6—6 of Figure 2,

Figure 7 is a sectional view taken on the horizontal plane indicated by the line 7—7 of Figure 2,

Figure 8 is a sectional view taken on the vertical plane indicated by the line 8—8 of Figure 7, and

Figure 9 is a detail view in end elevation of the valve for the air and steam pipes.

Corresponding and like parts are referred to in the following description and designated

in the several views of the accompanying drawings by similar reference characters.

Referring more in detail to the accompanying drawings, 1 designates the adjacent end portions of two railway cars and 2 the outer and 3 the inner longitudinal beams of the cars. The coupling of this invention, as illustrated in the present drawings, includes heads 4 which are adapted to be brought into inter-engaging condition during the coupling of the cars 1 and held in such engagement by means of pins 5, extensions or flanges 6 and ribs 7, after the cars have been coupled. Remote lateral sides of the heads 4 are forwardly and inwardly inclined, and the heads are provided near their other lateral sides with longitudinally extending openings 8. The ribs 7 which taper forwardly, are formed on the inclined sides of the heads 4, and the pins 5 extend forwardly from the forward ends of the ribs 7 and enter the openings 8 in the heads 4. The extensions 6 project forwardly from said other sides of the heads 4 and have forwardly inclined inner lateral sides which contact with the inclined sides of the heads. The ribs 7 have a snug fit in correspondingly shaped recesses 9 which are formed in the inner lateral sides of the flanges 6 and communicate at their inner ends with the openings 8. The forwardly and outwardly inclined bottom and the rearwardly converging side walls of the recesses 9 guide the pins 5 into the openings 8 while the cars 1 are being coupled. When the heads 4 are in interlocking engagement they are held against any relative horizontal or vertical movement, and they will readily separate after the cars 1 have been uncoupled.

The heads 4 are supported from the cars 1 by brackets 10 which are secured to the beams 3 by bolts 11 and are held against casual movement with respect to the cars by brace rods 12. The rods 12 are secured as at 13 to the beams 2 and as at 14 to the brackets 10. The brackets 10 comprise vertical rearward rods 15 and vertical forward rods 16 each pair of which are connected at their upper and lower ends by crossed brace rods 17. Horizontal cross pieces 18 and 19 and horizontal side pieces 20 are secured to the lower ends of the rods 15 and 16. The cross

pieces 18 are provided with angular recesses 21 which have their apexes located at the transverse center of said cross pieces. The heads 4 rest upon the cross pieces 18 and are provided with downwardly extending lugs 22 which are angular in cross section and normally occupy the apexes of the recesses 21. The heads 4 and the parts 23, 24 and 25 carried thereby are yieldingly held in contact with the cross pieces 18 and 19 by springs 26 which are mounted upon the rods 15 and 16 between stops 27 carried by said rods and pressure rods 28 and 29 slidably mounted on said rods and contacting respectively with the parts 23 and 25. The heads 4 are yieldingly held in their forwardmost position with the lugs 22 in the apexes of the recesses 21 by means of springs 30 mounted upon the parts 25 between the rearward sides of the heads and collars 31 which latter embrace the pipes 25 and are carried by rods 32 connected to and extending inwardly from the rods 16. The rods 32 are provided with threaded rearward end portions upon which the collars 31 are slidably mounted and are kept from being withdrawn therefrom by nuts 33 which latter may be adjusted to vary the tension of the springs 30. The parts 25 pass through openings 34 in guides 35 connected to the rods 15, and are capable of having slideable and rockable movements with respect to said guides. The heads 4 and the parts carried thereby are supported for vertical, lateral and longitudinal movements with respect to the cars 1 in order to prevent them from becoming uncoupled and to protect them from injury during relative vertical, lateral and longitudinal movements of the cars. The recesses 21, lugs 22 and springs 26 and 30 normally retain the heads 4 at the longitudinal center of the cars 1, and return them to such position immediately after the removal of the force as the result of which they were moved from such position.

The parts 25 are of hollow cylindrical formation, and are threadedly connected with the heads 4 and communicate with axial openings 36 in the latter. (See Fig. 5.) The cylinders 25 are adapted to be connected to the air pipes, not shown, of the cars 1 by hose 37. The parts 24 which are also of hollow cylindrical formation, are adapted to be connected to the steam pipes, not shown, of the cars 1 by hose 38, and are threaded in the inner ends of the parts 23 which constitute valve casings. The casings 23 are cylindrical and connected to the heads 4 by clamps 39, and the cylinders 24 are connected to the cylinders 25 by clamps 40. The casings 23 are provided with annular series of recesses 41 certain of which are adapted to receive pins 42 and 43 carried respectively by the heads 4 and clamps 39. The cylinders 24 and 25 are provided with annular series of recesses 44 certain of which are adapted to

receive pins 45 carried by the clamps 40. Should those parts of the casings 23 with which the bars 29 contact wear flat, the casings and the cylinders 24 may be turned to present other parts of the casings 23 for contact by the bars 29, and this may be readily done after first loosening or removing the clamps 39 and 40. The pins on the clamps 39 and 40 and on the heads 4 hold the casings 23 and cylinders 24 and 25 against casual 75 rotation.

The heads 4 and casings 23 are provided with rubber gaskets 46 (see Figs. 5 and 7) which are secured in place by ring nuts 47 and which, when the parts of the coupling are in engagement, establish leak proof connections between the heads 4 and between the casings 23. The gaskets 46 are provided with axial openings 48 which establish communication between the heads 4 and between the casings 23 and through which the forward ends of valve stems 49 pass. The stems 49 are carried by valve bodies 50 which are threaded in the openings 36 of the heads 4 and in the casings 23, and are provided at their inner ends with seats 51 for the valves 52 carried by the stems. The valves 52 are normally held seated by springs 53 which are mounted on the stems 49 between the valves and guides 54 removably carried by arms 55 extending rearwardly from the bodies 50. The other ends of the rods 49 are provided with heads 56 which are in contact when the parts of the coupling are in engagement, and due thereto the valves 52 are held unseated 100 and communication is established between the steam and air pipes of the cars 1.

From the foregoing description, taken in connection with the accompanying drawings, it should be apparent that the heads 4 will be brought into interengaging connection during the coupling of the cars 1, that when they are in such connection leak proof connections are established between them and between the casings 23, and that also when they are in such connection the valves 52 are unseated and communication is established between the air and steam pipes of the cars. It should also be understood that the coupling heads 4 are so supported on the cars 1 as to prevent relative movement of the latter from separating or imparting injury to the heads and parts carried thereby, that the springs 53 will seat the valves 52 immediately on the uncoupling and separation of the cars, and as the result prevent the escape of air and steam, and that the device may be readily secured to the cars and will not interfere with the coupling of the latter.

While I have described the principle of operation of the invention, together with the structure which I now consider to be the best embodiment thereof, I desire to have it understood that the device shown is merely illustrative, and that such changes may be 120

made when desired as are within the scope of the invention as claimed.

What is claimed is:—

1. An automatic train pipe coupling comprising vertical forward bars and vertical rearward bars, a horizontal cross piece secured to the forward bars, a horizontal cross piece secured to the rearward bars, a head resting upon said first cross piece, a cylinder carried by the head and resting upon said second cross piece, a valve carried by the head, a pressure bar slidably mounted on the forward bars and contacting with the head, a pressure bar slidably mounted on the rearward bars and contacting with the cylinder, springs mounted upon the rods and bearing upon the pressure bars, and crossed braces connected to the upper and lower ends of the forward and rearward bars at opposite sides 20 of the head and cylinder.
2. An automatic train pipe coupling comprising heads, each head having one of its sides forwardly and inwardly inclined and provided adjacent its other lateral side with a longitudinally extending opening, an extension projecting forwardly from the last mentioned side of the head and having its inner side forwardly and outwardly inclined, the projection of one head contacting with the inclined side of the other head and provided in its inner side with a recess communicating with the opening in the head, a forwardly tapering rib on the inclined lateral side of each head, the rib of one head fitting snugly in the recess of the extension of the other head, and a pin extending forwardly from the forward end of each rib, the pin of the rib of one head fitting in the opening of the other head.
3. In a structure for the purpose stated, a pair of pipe connecting heads, each having a longitudinally apertured body, having a forward face and lateral walls, and each body having one lateral wall receding from the longitudinal axis of the head, in a direction backwardly from the forward face of the head, the opposite lateral wall of the body being extended forwardly from the body and receding laterally away from the axis of the body, the two lateral walls of each head cooperating with the complementary walls of the other head.
4. In a coupling, a body having a longitudinal aperture for the passage of fluid under pressure, said body having a forward face disposed transversely of the longitudinal axis of the coupling to cooperate with a corresponding face of a like coupling member, and having a lateral face flaring away from the axis of the body at parts more remote from said forward face, said lateral face having a tapered rib extending therealong, said rib being narrower at its forward end and wider at its rearward end, the opposite lateral wall of the body being extended for

wardly and flared laterally away from the axis of the body and having a tapering groove therein to receive a rib on a lateral face of a similar cooperating coupling member.

5. An automatic train-pipe coupling, comprising a head, means for supporting the head from a car, a valved casing mounted upon the head, the same being adapted for rotational adjustment and provided with an annular series of recesses, a clamp secured to the head and embracing the casing and provided with a pin entering one of the recesses to hold the casing in adjusted position, and a spring pressed pressure bar carried by said means and bearing against the casing.

In testimony whereof I affix my signature.
